UNITED STATES PATENT OFFICE.

EDWARD ERICKSON, OF BEVERLY, MASSACHUSETTS.

FASTENING DEVICE.

1,083,925.

Specification of Letters Patent. Patented Jan. 13, 1914.

Application filed September 28, 1910. Serial No. 584,248.

To all whom it may concern:

Be it known that I, EDWARD ERICKSON, a citizen of the United States, residing in Beverly, county of Essex, and State of Massachusetts, have invented an Improvement in Fastening Devices, of which the following description, in connection with the accompanying drawings, is a specification, like letters on the drawings representing like parts.

This invention relates to a separable button or fastening device especially adapted among other uses to be employed on automobiles, motor-boats and like vehicles in connection with curtains, flaps and like coverings.

The invention has for its object to provide a simple, inexpensive and efficient fastening device, with which the curtain or other flexible device may be securely fastened against accidental disengagement, but which is capable of being readily disengaged from opposite sides of the curtain or like device, which makes the fastening device especially appropriate for use on motor and other boats provided with side curtains as a protection against the weather, as the danger of the occupants of the boat being unable to unfasten the curtains in case of accidents is avoided.

The fastening device comprises a male member, which is adapted to be secured to a rigid part of the vehicle, and a female member, which is secured to the curtain and is provided with an opening through which the male member is passed, said male member having a hollow stud or post provided with an elongated head and at one side with a laterally movable section, which is moved in one direction by a spring and in the other by the female member, as will be described. The spring-actuated section of the post or stud normally projects outwardly and operates with the stud or post to substantially fill the elongated opening in the female member, whereby the latter is prevented from being accidentally disengaged from the male member, as will be described.

The male member is provided with a head extended beyond the post and the movable section thereof in the normal position of the latter, so as to engage the opposite end walls of the opening in the female member and prevent the latter being disengaged by a direct pull or push, and the projecting end opposite the slot in the post is provided

with an upwardly, inclined under surface, against which the female member may be pulled or pushed to release or remove the female member from the male member, as will be described.

Figure 1 represents a fastening device embodying this invention with the members in their engaged position. Fig. 2, a view showing the members disengaged. Fig. 3, a section on the line 3-3, Fig. 1. Fig. 3^a, a like section with the female member about to be disengaged from the male member, and Fig. 4, a detail to be referred to.

In the embodiment of the invention shown in the drawing, the male member comprises a base *a* from which is erected a post or stud *b* provided with a head *c*.

The parts of the male member referred to, may and preferably will be made in one piece from sheet metal, such as brass, and said parts are made longer than they are wide.

The post or stud *b* is made hollow as herein shown and is provided at one end with a slot or opening *d*, which extends back from the end toward and into the sides of the post or stud.

The slotted end of the hollow stud or post has co-operating with it a movable section, preferably of sheet metal and comprising a curved center portion 10 and substantially straight sides 14, which extend into the hollow stud or post. The movable section is made of such height as to enable it to be moved into and out of the slot, it being moved outwardly to project through the slot by a spring within the hollow post or stud, said spring being shown in Figs. 3 and 3^a as a bent wire 15, which is soldered or otherwise fastened at one end to the back of the center portion 10, and has its other end extended up into the hollow stud toward the head thereof, and provided with a finger 16, which enters a recess 17 at one end of the head. The movable section of the post or stud is moved bodily outwardly by the spring 15 and inwardly by the female member, as will be described. The outward movement of the movable section is limited as herein shown by the spring 15 engaging the base plate *a*, as shown in Fig. 3.

The head *c* of the stud or post is provided with projecting ends 20, 21, which extend beyond the end wall 22 of the post or stud and beyond the movable section in its normal or outward position shown in Figs.

2 and 3. The projecting end 21 may be termed the front end, and the end 20 the rear end, and the latter is provided with an inclined under side 24, which extends to 5 the rear wall of the post or stud, for a purpose as will be described.

The male member is designed to be fastened as by screws 25 or otherwise to a stationary part 26 of the automobile, boat or 10 other vehicle and has coöperating with it a female member or gromet 30 of known construction and comprising as shown two substantially elliptical shaped metal pieces between which the curtain 31 is firmly clamped 15 in a manner well understood. The female member is provided with an elongated hole 32 of a length slightly greater than the distance from the center portion 10 of the movable section in its outward position and the 20 rear wall 22 of the post or stud, and less than the length of the head *c* of the post or stud, as represented in Figs. 1 and 3, so that when the female member is engaged with the male member as represented in Figs. 1 and 3, 25 the projecting ends 20, 21 of the head of the post or stud overlap the end walls of the slot 32 in the female member and prevent the latter from being disengaged accidentally by a direct movement of the female 30 member on the post or stud toward the head thereof, and thereby necessitating movement of the female member in the direction of its length and inward movement of the movable section of the post or stud, in order to engage 35 or disengage the female member with or from the male member, thereby effectively locking the two members together against accidental disengagement.

The female member is engaged with the 40 male member in the following manner: One end of the female member is passed over the projecting end 21 of the head *c*, and the female member is then moved longitudinally toward the projecting end 20 in the direction 45 indicated by the arrow 40, the female member being in an inclined position with relation to the base of the male member after the manner represented in Fig. 3a.

The female member on its movement in 50 the direction of the arrow 40 forces the movable section of the post into the same until the rear wall of the slot 32 passes over or by the projecting end 20 of the head, whereupon the curtain 31 is released by the operator, and the spring 15 forces the movable 55 section outwardly into its normal position shown in Figs. 1 and 3. The disengagement of the female member may be effected from the outside by pulling upon the curtain so as 60 to move the female member in the direction of the arrow 40 until the end wall 41 of the slot can be slipped from engagement with the projecting end 20, or the pressure may be applied from the inner or under side of 65 the curtain so as to force the rear wall 41 of

the slot 32 in the female member up the inclined under side 24 of the projecting end 20 until the wall 41 is forced off from the end 20. This feature of the fastening device enables it to be used on launches and other boats provided with curtains or side flaps, for in case of accidents, such as the boat or launch capsizing, the curtains could be forced open from within the boat and the occupants given a chance for their lives. 70 75 This feature is also useful in the case of automobiles, as the flaps can be quickly unbuttoned from within the vehicle.

I have herein shown one embodiment of the invention, but I do not desire to limit the invention to the particular construction 80 shown.

In Fig. 3, the spring 15 is represented as soldered to the movable section of the post or stud, but such spring can be integral with 85 said movable section as represented in Fig. 4.

Claims:

1. In a fastening device of the character described, in combination, a base, a hollow 90 post erected thereon and provided with a head extended in opposite directions beyond said post to form projecting ends, one of which is upwardly inclined on its under surface, said hollow post having an opening in 95 its side opposite the inclined projecting end, a sliding post section comprising a curved central portion to project through the opening in the said post, and substantially straight sides extended into the hollow post to slide therein and guide the sliding post section, and a substantially U-shaped spring 100 within the hollow post to force the sliding post section outwardly and to engage said base to limit the outward movement of said sliding post section, and a female member having an elongated slot of a length less than the head of the post and coöperating with the projecting ends of the latter to be retained on the post against removal by a 105 direct pull or push, and coöperating with the inclined under surface of one of said projecting ends to enable the female member to be disengaged from the outside of the male member by a pull exerted against the 110 said inclined surface or from the inside of the female member by a push against the said inclined surface.

2. In a fastening device of the character described, in combination, a male member 115 provided with a hollow post or stud having a slot in one side, a head provided with ends projecting beyond said post in opposite directions, the end of said head which is opposite to said slot having an upwardly inclined under surface, a spring-actuated section of said post or stud sliding within the latter and normally projecting through said slot, means to limit the outward movement 120 of said sliding section, and a female mem- 125 130

ber having an elongated slot of less length than said head and coöperating with the projecting ends of said head to be retained on the post against a direct pull or push and to be released from said post by a pull or push against the said inclined surface, substantially as described.

In testimony whereof I have signed my name to this specification in the presence of two subscribing witnesses.

EDWARD ERICKSON.
